UNITED STATES PATENT OFFICE.

JAMES L. PITTS, OF GRAND RAPIDS, MICHIGAN.

SAW-SWAGE.

SPECIFICATION forming part of Letters Patent No. 259,423, dated June 13, 1882.

Application filed January 11, 1882. (No model.)

To all whom it may concern:

Be it known that I, JAMES L. PITTS, of the city of Grand Rapids, in the county of Kent and State of Michigan, have invented a new 5 and useful Saw-Swage, of which the following is a specification.

My invention relates to an improved saw-swage, so constructed as to be readily and quickly adjusted to saw-teeth of any size; and 10 the object is to enable the operator to swage and draw out the teeth of a saw in proper form and shape to be the most efficient, more quickly and better than can be done by any device now in use. I attain this object by 15 means of the mechanism illustrated in the accompanying drawings, in which—

Figure 1 is a perspective view of my saw-swage, and Fig. 2 is a side view of the same, showing the method of applying it to the saw-teeth to be operated on.

Similar letters refer to similar parts throughout the several views.

In the drawings, H represents the swage proper, one end terminating in a suitable handle of suitable form and size to be readily grasped by the hand, while the other turns or bends at right angles with the handle, as shown in Fig. 1. This part tapers toward the end farthest from the handle, as shown, and 25 is provided with several grooves, (shown by a a a in Fig. 1,) which grooves slope down in front toward the swage-plate K.

The plate K is constructed of tempered steel, and also tapers or decreases in size to correspond with the swage proper, as shown in the 30

drawings. This part K is keyed in or slid in to the handle in a groove, so as to be readily and quickly removed and replaced by a new one, if desired.

The bend X in the handle is designed to allow the swage to be held under a tooth and pressed downward, so that a saw-tooth may fit into this bend, thus allowing the swage to be readily used at the largest point.

In using my invention the grooved portion 45 is placed downward in cases where the saw-teeth are up, so that one groove fits over one tooth, as shown on tooth T. Then, by lowering the handle, the point of tooth T' is brought just over the edge of the swage-plate K, as 50 shown in Fig. 2. Then, by a small hammer, the point of the tooth is flattened or drawn out into the form required.

The swage and plate K, diminishing in size, allow the device to be applied to saw-teeth 55 of all sizes, which adjustability is still further increased by the sloping grooves a a a, as above described.

Having thus described my invention, what I claim to have invented, and desire to secure 60 by Letters Patent, is—

As a new article of manufacture, the saw-swage constructed of the part H H, provided with grooves a a a, and keyed swage-plate K, all constructed as and for the purposes de- 65 scribed.

JAMES L. PITTS.
